UNITED STATES PATENT OFFICE

150,018

DESIGN FOR AN EARRING

Anthony R. Lo Curto, Brooklyn, N. Y.

Application January 25, 1947, Serial No. 136,421

Term of patent 3½ years

(Cl. D45—9)

To all whom it may concern:

Be it known that I, Anthony R. Lo Curto, a citizen of the United States residing in Brooklyn, in the county of Kings and State of New York, have invented a new, original, and ornamental Design for Earring, of which the following is a specification, reference being had to the accompanying drawing, forming part thereof:

I claim:

The ornamental design for an earring, as shown.

ANTHONY R. LO CURTO.
